UNITED STATES PATENT OFFICE.

ADAM C. WILLIAMS, OF RAVENNA, OHIO.

DESIGN FOR A TOY BANK.

40,245.

Specification for Design.

Patented Aug. 31, 1909.

Application filed June 30, 1909. Serial No. 505,282. Term of patent 14 years.

To all whom it may concern:

Be it known that I, ADAM C. WILLIAMS, a citizen of the United States of America, residing at Ravenna, in the county of Portage and State of Ohio, have invented a new, original, and ornamental Design for Toy Banks, of which the following is a specification, reference being had to the accompanying drawings, forming part thereof.

In the drawings, Figure 1 is a front elevation, and Fig. 2 a rear elevation of a toy bank, showing my new design.

I claim:

The ornamental design for a toy bank as shown.
